DESIGN FOR A HANDBAG

Harry Morris, Chicago, Ill.

Application May 31, 1943, Serial No. 110,329

Term of patent 3½ years

To all whom it may concern:

Be it known that I, Harry Morris, a citizen of the United States, residing in Chicago, in the county of Cook and State of Illinois, have invented a new, original, and ornamental Design for a Handbag, of which the following is a specification, reference being had to the accompanying drawing, forming part thereof.

Fig. 1 is a front elevational view of a handbag, showing my design in closed position.

Fig. 2 is another elevational view of the bag

shown in Fig. 1, illustrating the handbag in open position, and

Fig. 3 is a side elevational view of the handbag shown in Figs. 1 and 2 in closed position.

The rear elevational view of the handbag is the same as the front view.

I claim:

The ornamental design for a handbag, substantially as shown and described.

HARRY MORRIS.
